F. J. FLAJOLE

STEEL HEATING BOILER

Filed Oct. 24, 1922

FIG. 1

FIG. 2

FIG. 3

Frank J. Flajole

BY

Harry Bowen

ATTORNEY

UNITED STATES PATENT OFFICE.

FRANK J. FLAJOLE, OF SEATTLE, WASHINGTON.

STEEL HEATING BOILER.

Application filed October 24, 1922. Serial No. 596,575.

To all whom it may concern:

Be it known that I, FRANK J. FLAJOLE, a citizen of the United States, residing at Seattle, county of King, and State of Washington, have invented a new and useful Steel Heating Boiler; and I do hereby declare that the following is a full, clear, and exact specification, such as will enable others skilled in the art to which it appertains to 10 make and use the same.

The invention is a heating boiler which is constructed of steel and designed so that it will yield the highest possible efficiency.

The object of the invention is to construct 15 a heating boiler in which the fire box and flues are completely surrounded by water.

Another object of the invention is to provide a heating boiler that is made of steel in which the horizontal division plate below 20 the tubes is directly connected to the shell.

And a further object of the invention is to provide a steel heating boiler in which the sediment will not be collected on the plate which forms the top of the fire box.

25 With these ends in view the invention embodies a steel shell in which is an inner shell with an arched top, forming the fire box, and a horizontal partition between the top of the fire box and the tubes which is semi-circular and whose ends, which extend upward, are welded to the outer shell. Both sides of the outer shell curve inward at the point midway between the fire box and the tubes so that they will withstand a greater 35 pressure. The tubes are installed above the horizontal partition and are arranged in two sets so that the gases will pass forward through the lower set and then backward through the upper set to the flue. The entire fire box is water jacketed and these jackets are open to the steam chest above.

Other features and advantages of the invention will appear from the following description taken in connection with the drawings, wherein:—

Figure 1 is a part cross section on the line 1—1 of Figure 3.

Figure 2 is a cross section on the line 2—2 of Figure 3.

50 Figure 3 is a longitudinal section with parts of the exterior shown.

In the drawings I have shown my boiler as it would be constructed wherein numeral 1 indicates the plate which forms the sides and arch top of the fire box and this plate

is split in the center from the point 2 to the rear end and bent upward to form the sides 3 and 4 as shown in Figure 2. Another plate 5 is corrugated at the top and then bent downward to meet the ends of the plates 3 and 4 and these ends are welded together. The lower ends of the plate 1 are bent outward as shown in Figures 1 and 2 so that the lower ends of the shell may be welded to them. Another plate 6 may be 65 connected to the plate 5 and to the rear edges of the plate 1 and then extended downward to the bottom of the shell where it is bent outward so that the shell may be welded to it in a similar manner as to the ends of the plate 1. Another tube plate 7 is connected to the forward end of the plate 5 and also to the top of the arch formed by the plate 1. Or one plate may be used to take the place of the plates 5, 6 and 7. These plates are 70 surrounded by another plate 8 forming the shell which may extend up one side, around the top, and down the other side so that its lower ends may be welded to the outstanding ends of the plates 1 and 6. Another plate 9 75 forming a horizontal partition may be bent in the shape of an arc and welded to the shell 8 at its ends 10 and also through the rivet holes 11. This plate may have openings 12 in it so that water may pass through it from the chamber surrounding the fire box to the chamber surrounding the tubes, and this plate may be attached to the top of the arch over the fire box by bolts 13 or in any desired manner. Another plate 14 may be 80 connected to the front end of the shell to form the front of the boiler and another plate 15 may be connected to the rear end to 85 form the rear end of the boiler; and a chamber 16 may be placed at the front which may have a door 17 in it. A clean-out door 18 may be placed in the plate 14 just above the partition 9 so that any sediment collected 90 on the partition may be removed.

Two sets of tubes 19 and 20 may be placed 100 in the space above the fire box to carry the gases first forward and then backward similar to any horizontal fire tube boiler and short bolts 21 may be placed at spaced intervals completely around the fire box to hold the inner shell to the outer, and long bolts 22 may be placed through the boiler as shown in Figures 1 and 3.

Any type of base may be used which may have a grate 23 below the fire box, a baffle 110

wall 24 behind it and an ash pit 25 below it; and any suitable type of doors may be used for the fire and ash doors.

It will be understood that changes may be made in the construction without departing from the spirit of the invention. One of which changes may be in the use of different radii for the curves of the shell or the fire box, another may be in the use of more or less tubes or in the change of the size, and another may be in the type of connection between the two sides or between the partition and the top of the arch.

The construction will be readily understood from the foregoing description. To use the device it will be assembled as shown and as fire is started in the fire box the gases will pass upward and then forward through the tubes 19 to the chamber 16 from where they will then pass backward through the tubes 20 to the flue. It will be seen that the entire fire box will be surrounded with water, with the exception of the bottom and as the top is arched there will be no corners where air pockets may be formed. It will also be seen that the partition 9 not only acts as a support for the two sides but will catch all sediment from the upper section of the boiler so that this sediment will not be permitted to drop on the plate directly above the fire box. As the water is heated it will pass upward from the section surrounding the fire box through the holes 12 in the partition 9 to the upper section surrounding the tubes and from the top of this section it may be drawn off through any suitable connection or by only filling the boiler to a point just above the top row of tubes the water may be converted into steam and the steam may be drawn off in any desired manner.

Having thus fully described the invention what I claim as new and desire to secure by Letters Patent, is:—

1. In a boiler having a fire box and fire tubes above the fire box, an outer shell being formed of steel plate and being bent inward at a point midway between the fire box and the tube section, an inner plate forming a fire box with the upper part bent to form the upper half of a circle and constructed so that a space will be left between it and the outer shell, stay-bolts between this plate and the outer shell, another plate bent to form the lower half of a circle above the fire box, said plate having openings through it and having its edges welded to the outer

shell, a connection between the bottom of this plate and the top of the plate forming the fire box, an opening in the top of the fire box at the rear of the boiler formed by splitting the plate forming the fire box a short distance from the rear end and bending the edges upward, a corrugated plate forming the top of this section at the rear and being connected to the edges of the former plate and to a tube plate at the front, another plate forming the rear of the fire box being connected to the plate forming the fire box and to the corrugated plate and having a space between it and the outer shell, stay-bolts between this plate and the outer shell, and a welded connection between the lower ends of all the plates forming the inner shell and the outer shell.

2. In a boiler having a fire box with fire tubes above, an outer shell formed of steel plate and curved inward at a point midway between the fire box and the tube section, an inner shell which forms the fire box and the upper portion of which is bent to form the upper half of a circle and arranged with a space between it and the outer shell, said inner and outer shell having stay-bolts between them, another plate bent to form the lower half of a circle above the fire box which has openings through it and its edges attached to the outer shell, said plate being attached to the plate forming the top of the fire box at the center, said fire box having an opening at the rear which is formed by splitting the plate forming the fire box a short distance from the rear and bending the edges upward, and said opening being covered by corrugated plate which is connected to the edges of the former plate, and said inner and outer shells having their lower edges connected by welding.

3. A boiler of the class described having an inner shell forming a fire box, an outer shell, the walls of said inner and outer shells being held together by stay-bolts, a circular tube section above said fire box, sections at opposite sides of the outer shell being bent inwardly between the fire box section and the circular tube section, an opening at the rear of the fire box, a false bottom under the circular tube section, a corrugated cover for the opening at the rear of the fire box, the said sections of the outer shell that are bent inwardly being rigidly held together by stay-bolts.

FRANK J. FLAJOLE.
